LANDS

AMPLIFYING INSTALLATION

Application filed October 15, 1930, Serial No. 488,965, and in the Netherlands December 21, 1929.

This invention relates to an amplifying system for use with devices for electrically reproducing sound vibrations.

In the known devices of this type the electrical oscillations produced by the apparatus for translating the sound vibrations into electrical oscillations, which may be effected by means of electric pick-up devices, microphones and the like, are amplified, whereupon these amplified oscillations may be delivered to several groups of loud speakers which are connected, for example, in parallel.

The invention relates particularly to an amplifying system in which the said apparatus is connected, preferably through the intermediary of a preliminary amplifier, to at least two amplifying units, each of which feeding a group of reproducing units. By the term "amplifying unit" is to be understood hereinafter one or more cooperating amplifiers feeding a group of reproducing units. This arrangement may be advantageously used, for example, with amplifying systems of apparatus for reproducing acoustic films and of installations for use in addressing large audiences from a central point by means of some groups of loud speakers placed at various points of the space occupied by the audience. With the first mentioned apparatus a plurality of loud speakers is preferably placed in the vicinity of the projection screen, said loudspeakers being connected to a corresponding amplifying unit. All amplifying units may be fed with electrical oscillations delivered, for example, by an electric pick-up device, microphone, radio-receiving apparatus and the like. Such an arrangement has the drawback however, that a whole group of reproducing units is rendered inoperative if one of the amplifying units breaks down. This constitutes a serious drawback especially with apparatus for reproducing talking pictures, since the remaining sound reproduced by the other group of loud speakers, comes only from one side of the projection screen due to which the effect of the sound reproduction from both sides is entirely lost. If the groups of loud speakers be disposed in a vertical plane on either side 50 of the projection screen this drawback makes

itself less manifest than if the groups are located in a horizontal plane above and beneath the projection screen.

In order to avoid this difficulty the amplifying system according to the invention is provided with a switching device interposed between an amplifying unit and a group of reproducing units. By means of said device the group of reproducing units corresponding to a defective amplifying unit may be switched into the output circuit of one or more of the other amplifying units. In this manner the said drawback may be avoided, since the intact amplifying unit or units receive the load of the group of reproducing units corresponding to the defective amplifying unit. Of course, the changing over will not fail to make its influence felt on the amplifying units to which the additional load is supplied, but by a suitable choice of these units the sound reproduction may be readjusted so as to obtain substantially the same effect.

It will be obvious that if one of the amplifying units breaks down a group of reproducing units will be put out of service, though for a short time only. The duration of the period of interruption depends on the time required for tracing the defective unit and for changing over the corresponding group of reproducing units to one or more of the other amplifying units. Though this interruption period is of a short duration only, the sound reproduction is unfavourably influenced thereby. This drawback may be avoided by distributing the reproducing units of each group or of most of the groups about the various amplifying units. If one of the amplifying units breaks down only one or a few units of each group or of most of the groups of reproducing units will be rendered inoperative, while with talking film apparatus, for example, the effect of the reproduction will substantially be conserved.

The invention will be more clearly understood by reference to the accompanying drawing representing, by way of example, some embodiments thereof.

Fig. 1 is a schematic diagram of an am-

plifying system showing the principles underlying the invention.

Fig. 2 is a diagram of an amplifying system according to the invention for use in apparatus for reproducing acoustic films.

Fig. 3 is a diagram of another form of construction of an amplifying system embodying the invention.

Fig. 1 shows a microphone 1, which is connected to an amplifier 2 by which the electric currents delivered by the microphone are amplified, these amplified currents feeding the input circuits of two amplifiers 3 and 4 which are mounted in parallel. The amplifiers 3 and 4 are connected to groups of loud speakers 5 and 6 respectively which are placed at various points of the space. Consequently the energy delivered by the microphone is distributed about both groups of loud speakers through the intermediary of the amplifiers.

Fig. 2 is a diagram of a device for use in reproducing talking films in which 7 is an electric pick-up device which is connected to an amplifying device 8, whose output energy is distributed about the input circuits of the amplifiers 9 and 10 which are connected in parallel. Each of the amplifiers 9 and 10 is connected across change-over switches 11 and 12 to a group of loudspeakers 13 and 14 placed respectively on either side of the projecting screen 15. By means of the change-over switches 11 and 12 the group of reproducing units corresponding to a defective amplifying unit may be changed over to one or more of the other amplifying units. As appears from the drawing the connection between the amplifying units and the reproducing units will be established through the contacts 16 and 18 during the normal operation. If, for example, the amplifier 10 breaks down, then one has only to change over to the contact 17, so that the amplifier 9 receives the load of the group of reproducing units 13.

Fig. 3 shows schematically an amplifying system for use with the so-called public address system in which a large audience is addressed from a central point, 19 and 20 and 21 are amplifying units which are jointly fed from the apparatus, for example, from a microphone, delivering the electric oscillations which must be transformed into acoustic vibrations by the groups of reproducing units, for example, by loud speakers which are placed at various points of the space occupied by the audience.

The amplifiers 19, 20 and 21 respectively are connected to the loud speaker groups 25, 26 and 27 through the intermediary of change-over switches 22, 23 and 24. Each of these groups comprises six loud speakers which are connected in parallel in pairs. As appears from the drawing each pair of loud speakers of each group is connected to the

change-over switches 22, 23 and 24 respectively.

Each of the change-over switches which are represented schematically, comprises three contacts 19, 20 and 21 of which the middle contact establishes the connection between the amplifiers and the corresponding groups of loud speakers in the normal working position. If, for example, the amplifier 19 breaks down two specimens of each group of loud speakers will be rendered inoperative, so that the sound distribution remains substantially the same. Consequently the operator is not hurried in tracing the defective amplifier. After the latter has been found the corresponding loud speaker group, viz. the group 19, may be changed over to one of the amplifying units 20 or 21 by changing over from the contact 19 of the change-over switch 22 to the contact 20 or 21, whereupon this amplifying unit may be readjusted, thus obtaining a reproduction substantially corresponding to that obtained formerly. By proceeding in this manner the influence of disturbances may be greatly reduced.

The amplifiers 19, 20, and 21, are connected to a common amplifier 8, in turn connected to an electric pick up 7.

What we claim is:

1. An amplifying system for use with apparatus for electrically reproducing acoustic vibrations, comprising a plurality of amplifier units fed from a common source, a plurality of groups of loud speakers, all of substantially the same characteristics, each group of loud speakers being subdivided into sets of loud speakers, each set of each group of loud speakers being normally fed by a particular amplifier unit separate from those by which the remaining sets of each group are fed, and a plurality of switching means interposed, one between each group of loud speakers and each amplifier unit, for switching, upon break down of one of the amplifier units, the sets of loud speakers comprising the load thereof among the other amplifier units.

2. An amplifying system for use with apparatus for electrically reproducing acoustic vibrations, comprising a plurality of amplifier units fed from a common source, a plurality of groups of loud speakers, all of substantially the same characteristics, each group being subdivided into a plurality of sets of loud speakers, the corresponding set of each group of loud speakers being connected as the load of a particular amplifier unit, and switching means interposed, one for each of the said amplifier units, between said amplifier units and said groups of loud speakers for distributing upon break down of one of the amplifier units, the load thereof among the other amplifier units.

3. An amplifying system for electrically reproducing acoustic vibrations in conjunc-

tion with a public address system, comprising a plurality of amplifier units fed from a common source, a plurality of groups of loud speakers distributed about the distribution area of the reproduced acoustic vibrations, all the loud speakers having substantially the same characteristics each group being subdivided into a plurality of sets of loud speakers, each set of each group being fed by a different amplifier unit than that which feeds the other sets of that group, and switching means, one for each amplifier unit, for switching, in the instance of break down of one of the amplifier units, the sets of loud speakers forming the load thereof among the loads of the other amplifier units.

4. An amplifying system for use with apparatus for electrically reproducing acoustic vibrations, comprising a central amplifier, a plurality of amplifying units branched from and fed by said central amplifier, groups of loudspeakers fed from said amplifying units, all of the loudspeakers having substantially the same characteristics, said groups being placed at various points in space and being electrically divided into subgroups, a subgroup of one group of loudspeakers being connected into the circuit of one amplifying unit together with a subgroup of the other groups of loudspeakers, and switching means interposed between said groups of loudspeakers and said amplifying units for switching, upon breakdown of one of the amplifier units, the loudspeakers forming the load thereof into the load of at least one of the other amplifiers.

In testimony whereof we have signed our names to this specification.

WILLEM SIX.
